UNITED STATES PATENT OFFICE.

FREDERICK W. HOCHSTETTER, OF DAYTON, OHIO.

DESIGN FOR A MOVING-PICTURE MACHINE.

59,958.

Specification for Design.

Patented Dec. 13, 1921.

Application filed December 13, 1920. Serial No. 430,588. Term of patent 14 years.

To all whom it may concern:

Be it known that I, FREDERICK W. HOCHSTETTER, a citizen of the United States, residing at Dayton, in the county of Montgomery and State of Ohio, have invented a new, original, and ornamental Design for a Moving-Picture Machine, of which the following is a specification, reference being had

to the accompanying drawings, forming part thereof.

The figure is an elevation in perspective illustrating a moving picture machine.

I claim:—

The ornamental design for a moving picture machine, as shown.

FREDERICK W. HOCHSTETTER.
